LINE-SECTIONALIZER INTEGRATOR

Andrew W. Edwards and James M. Wallace, East
McKeesport, Pa., assignors to Westinghouse
Electric Corporation, East Pittsburgh, Pa., a
corporation of Pennsylvania

Application July 21, 1950, Serial No. 175,276

27 Claims. (Cl. 317—22)

1

Our invention relates to novel time-delayed resetting-means for automatically resetting the integrators or counting-mechanisms of line-sectionalizers. With slight modifications, however, the invention could be used in the counting-mechanisms of reclosers or other devices.

Line-sectionalizers and reclosers are used on rural alternating-current distribution-lines. The recloser is used between the distribution-line and the electric power-source. This recloser responds to predetermined overcurrent-conditions, indicative of a fault, and quickly opens its line-contact, after which it quickly recloses said contact, and if the fault has not automatically cleared itself during the period of deenergization of the line, the recloser quickly again opens its line-contact, and keeps up this process for a predetermined number of rapidly repeating cycles, usually four, and if the fault still persists this time, the recloser opens up its line-contact and locks it open, thereby permanently deenergizing the line until the line can be repaired. The function of the line-sectionalizer is to break up the line into sections, each section being controlled by a sectionalizer, which counts a predetermined rapid succession of overcurrent-conditions, for a number of times which is less than the recloser-times, and then opens its sectionalizer-contact during a no-current period of the recloser. In this way, a faulted section is removed by the sectionalizer, before the recloser permanently trips out the entire distribution-system.

In the case of both the recloser and the sectionalizer, it is necessary for the integrator or automatic counting-mechanism to be self-resetting. Ordinarily, this resetting is accomplished by slowly biasing a forwardly-ratcheted counter-member so that it will slowly return to its original unadvanced position whenever it is displaced at all. This requires some sort of time-delay device for resetting the counter-mechanism. Oil-dashpots for this purpose present problems of oil-leakage, evaporation, etc. Mechanical timers are usually too expensive for these applications. Air-dashpots for resetting the counter-member have the disadvantage of an inherently short travel and considerable backlash, so that it is difficult to use such air-dashpots directly on the forwardly ratcheted counter-member, so as to allow said counter-member to integrate its travel, and still allow resetting.

Our present invention is an improvement over an invention of Andrew W. Edwards and Earl F. Beach, Serial No. 175,273, filed concurrently herewith, relating to the broad idea of providing a

2

holding-detent for the advanced positions of the counter-rod, and releasing this holding-detent by means of any suitable form of light-weight time-delay means, such as an air-dashpot.

Our present invention relates to the provision of an electro-thermal time-delay means, such as a current-traversed bimetallic element, or other current-responsive time-delay means, for controlling the release of the holding-detent. Such a bimetallic member may be released either during its cooling cycle or during its heating cycle. One feature of our invention provides a means which is responsive to the current traversing the magnetizing coil, for energizing the time-delay device with a current having a limited magnitude.

With the foregoing and other objects in view, our invention consists in the systems, combinations, apparatus, parts, and methods of design and operation, hereinafter described and claimed, and illustrated in the accompanying drawings, wherein Figures 1 and 2 are somewhat diagrammatic elevational views, partly in section, showing two illustrative forms of embodiment of our invention.

25 The drawings are intended more to illustrate the principle of the invention, rather than its precise structure. While the invention is shown in the drawings, and will be described, as being embodied in a line-sectionalizer, it is to be understood that the counting-mechanism part of the illustrated structure, to which our invention particularly relates, may be used also in reclosers and perhaps also in other devices, with suitable modifications.

30 35 The illustrated line-sectionalizer is shown in Fig. 1 as being mounted in a cylindrical porcelain insulator 1, which normally stands in an essentially vertical position. One of the line-terminals, L1, is connected to the top-plate 2 of the sectionalizer, while the other line-terminal, L2, is connected to the bottom plate 3 of the sectionalizer. The sectionalizer is supported by a centrally located mounting-bracket 4, which is usually secured somewhere up on a pole (not shown).

40 45 On the underside of the top-plate 2 is shown the spring-pressed stationary contact-member 5 of the sectionalizer-contact or disconnect-switch, which is connected in series with the distribution-line. The movable contact-member of this combination is shown in the form of a vertically movable contact-rod 6, which normally presses up into contact with the stationary contact 5. The contact-rod 6 is normally biased downwardly, in 50 a contact-opening direction, not only by its own

weight, but also by a tension-spring 7. The bottom end of the contact-rod extends down below the bottom plate 3, and is provided with a looped operating-terminal or hookeye 8 which can be engaged by a switch-stick (not shown) for manually reclosing the sectionalizer-contact.

An intermediate portion of the vertically movable contact-rod 6 is provided with a shoulder 10 which is engaged by the latch-pin 11 of a pivotally supported latch-member 12, which is provided with a horizontally extending arm 13 which has to be pushed up in order to release the latch-pin 11 from its normal position under the rod-shoulder 10.

The vertically movable contact-rod 6 is also provided with a flexible current-carrying cable 14 which is secured to one end of a magnetizing coil 15, the other terminal of which is connected to the base-plate 3, as indicated at 16.

The magnetizing coil 15 is a part of an electromagnet device which has upper and lower pole-piece plates 21 and 22, and also a vertically movable armature 23 which moves vertically inside of the coil 15. In the form of embodiment of our invention which is shown in Fig. 1, the armature 23 is biased upwardly, into its normal unattracted position, by means of a compression-spring 24. The armature 23 moves up and down between a predetermined retracted upper position, as shown, and an advanced lower position when the bottom of the armature 23 is attracted magnetically down to, or nearly to, the lower pole-face plate 22 of the electromagnet-structure.

Slidably mounted at one side of the magnetizing coil 15, is a vertically movable counter-bar 30, which is normally biased, as by gravity, to its lowermost position, and which is upwardly advanceable, in discrete steps, until its top end 31 pushes up on the latch-arm 13 and unlatches the vertically movable contact-rod or trip-rod 6. The lower end of the counter-bar 30 extends below the sectionalizer-bottom 3, and is provided with a looped operating-terminal or hookeye 32, which may be engaged by a switch-stick (not shown) for manually pushing up on the counter-rod 30 and tripping out the sectionalizer. The upper portion of the counter-rod 30 is provided with a series of vertically spaced notches or shoulders 33, which are used in the step-by-step vertical advancement of the counter-rod, and also in temporarily holding the counter-rod in advanced position, as will be subsequently described.

The top of the armature 23 in Fig. 1 carries a horizontal arm 35 which is pivotally attached to a counter-advancing pawl or ratchet 36, which cooperates with the notched counter-rod 30. Each time the armature 23 returns upwardly to its unattracted position after having been pulled downwardly by a sufficiently strong over-current-energization of the magnetizing coil 15, the horizontal arm 35 rises and tilts the counter-pawl 36 into its operative position, as shown in Fig. 1, so that this pawl engages one of the lifting-notches or shoulders 33 on the counter-rod 30, and then lifts this shoulder through a predetermined distance, thus constituting the first movement in the step-by-step vertical advance-movement of the counter-rod 30.

The top end of the counter-rod 30 is held in any one of a plurality of advanced positions by means of a holding-detent or pawl 37, which is vertically spaced above the counter-pawl 36. In the form of our invention which is shown in Fig.

1, the holding-detent 37 is normally in an inoperative position, in which it does not engage under any of the notches or shoulders 33 on the counter-rod 30. This holding-detent 37 is actuated by means of an electro-thermal time-delay device, which is illustrated in the form of a bimetallic element 38 which is mounted on a suitable support 38'.

The bimetallic element 38 is supplied with a current-supply circuit 39 which preferably supplies a current which is approximately proportional to the line-current, or to the current through the magnetizing coil 15, but which is preferably limited as to its permissible overcurrent magnitudes. A convenient means to this end is associated with the electromagnet-structure, in which we have provided a small-cross-section core-portion or magnetizable-rod 40, which is disposed between the upper and lower pole-face plates 21 and 22, outside of the coil 15. This small-sectioned rod or core 40 in Fig. 1 saturates under overcurrent-conditions, which are in excess of the minimum overcurrent-condition necessary to actuate the magnetizing coil 15. This saturable core 40 is also magnetically shunted by means of a magnetic circuit-member 41 having an air gap 41' therein, so that, when the rod 40 saturates, the heavy magnetic flux is forced to travel across the air gap 41'. The saturable rod 40 is provided with a suitable secondary transformer-winding 42, which energizes the supply-circuit 39 for the bimetallic member 38.

The operation of the sectionalizer shown in Fig. 1 is as follows. Upon the occurrence of a sufficient overcurrent, the magnetizing coil 15 draws the armature 23 downward and compresses its spring 24. The increased alternating flux in the electromagnet, due to this overcurrent-condition, increases the output-current of the secondary coil 42 to the point where it quickly overheats the bimetal member 38 and causes it to be deflected into the dotted-line position shown in Fig. 1, wherein it moves the holding-detent 37 into an operative position in which it is in readiness to hold the counter-rod 30 in advanced positions when it is advanced in the counting-direction. The downward attraction of the armature 23 moves the counter-advancing pawl 36 downwardly, in readiness to ratchet the counter-bar 30 one step upwardly on the return-stroke of the armature.

When the line-current is interrupted by the associated recloser (not shown), or from any other cause, the armature 23 of Fig. 1 immediately returns upwardly to its original position, under the bias of its spring 24, and the counter-advancing pawl 36 advances the counter-rod 30 upwardly by a little more than the distance between successive notches or shoulders 33. During this upward advance of the counter-rod 30, the holding-detent 37 is deflected sufficiently by the contour of shoulder 33 so as to move under one of the notches or shoulders 33, in readiness to hold the counter-rod in the first step of its advanced position.

If a predetermined number (say three) of such operations occur in rapid succession, the counter-rod 30 will be advanced upwardly, step by step, until the latch-arm 13 is tripped, and the disconnect rod 6 is released, to move downwardly and interrupt the circuit at 5.

The bimetallic element 38 has such a thermal capacity, or snap-action, or both, that it will not cool off sufficiently to inactivate the holding-detent 37 during brief no-current pe-

riods of the recloser (not shown) but if the line-current should permanently become zero, or even if the line-current should assume normal values, the bimetallic element 37 will gradually cool and return to its normal position, illustrated in full lines in Fig. 1, thus disengaging the holding-detent 37 from the counter-rod 30, and permitting the counter-rod to immediately reset by gravity.

Since the line-sectionalizer must operate over a wide range of overcurrents, some of which may be several times the magnitude of the minimum fault-current which will actuate the armature 23, it is usually desirable to limit the possible maximum value of the overcurrent which is applied to the bimetallic device 38, so as to 10 avoid the danger of burning it out. This is taken care of by using a small magnetic cross-section for the core 40 of the secondary coil 42, and putting a gap 41' in parallel thereto. Thus, at some current-value which is slightly above 20 the minimum operating-current of the sectionalizer, the limited-section core 40 will saturate, and any additional flux will be carried by the gap 41'.

Fig. 2 illustrates a modification of our device 25 in which the holding-detent 37' is released by the heating of the bimetallic element 38'' on normal current-flow, rather than by cooling. In this case, the armature 23' is disposed so that it normally projects down below the lower end 30 of the magnetizing-coil 15, and its biasing-spring 25' is disposed above it, to bias it downwardly. This armature 23', in Fig. 2, is provided with an upwardly extending armature-rod 43, an intermediate portion of which carries the previously described arm 35 for advancing the counter-rod 30.

The holding-detent 37', in Fig. 2, is shown as being horizontally displaceable in a guide-member 46, and as being normally withdrawn out of engagement with the counter-rod 30, by means of a spring 45. The rear end of the holding-detent 37' is in engagement with a bellcrank 43 which is rocked by the top of the armature-rod 43 when the latter moves up into its overcurrent-position, and this rocking of the bellcrank moves the holding-detent over into its operative position in which it can latch under one of the notches or shoulders 33 of the counter-rod 30. This holding-detent 37' is provided with a latch-pin 47 which is adapted to be held over by a latch 48 on the bimetallic element 38'' when the holding-detent 37' is in its operative position.

In Fig. 2, the terminals of the heater-energizing circuit 39' are connected respectively to the fixed end of the bimetallic element 38'' and the holding-detent 37'. The energizing-circuit 39' for the bimetallic element 38'' is thus normally open, and is closed when the holding-detent 37' is pushed over to its operative position, wherein said circuit 39' is closed by the engagement of the latch 48 of the bimetallic element behind the latch-pin 47 of the holding-detent. Thereafter said circuit 39' remains closed until the heating of the bimetallic element 38'' causes it to deflect to its dotted-line heated position, wherein it releases the latch-pin 47, permitting the holding-detent 37' to move back to its inoperative position under the pull of its spring 45.

In the operation of the line-sectionalizer of Fig. 2, the first occurrence of an overcurrent-condition advances the armature 23' upwardly, and thus advances the counter-rod 30 one notch upwardly, and also moves the holding-detent 37'

over into its operative position in readiness to prevent the falling back of said counter-rod 30. This adjustment of the holding-detent closes the heater-circuit 39' and causes the energization of the bimetallic element 38'' for the brief moment during which an overcurrent-condition lasts. When the overcurrent is interrupted by the recloser or protective device (not shown), the armature 23' drops back, bringing with it the counter-detent 36, while the bimetallic element 38'' holds the holding-detent 37' in position, and the holding-detent holds the counter-bar 30 up in its first advance-step. The brief impulse of overcurrent is far too small to heat the bimetallic element to its thermally responsive temperature, particularly as the saturating point of the saturable secondary core may now (in Fig. 2) be chosen to correspond to a normal current-value.

If the fault which caused the overcurrent-condition clears itself before the predetermined count for which the integrator or counter is set, in Fig. 2, the normal load-current of the line will continue to energize the heater-circuit 39', and hence the bimetallic element 38'', for awhile; and after any suitable time-delay this bimetallic element 38'' will heat up, release the holding-detent 37', and deenergize its energizing-circuit 39' at 47 and 48. The release of the holding-detent 37' lets the counter-bar drop back immediately to its reset position.

If the fault persists, the sectionalizer of Fig. 2 will advance its counter-bar 30 for the predetermined number of steps, during recurrent overcurrent-conditions; and during the last overcurrent-condition said counter-bar will trip-out the trip-lever 13, releasing the trip-pin 11 from its holding-engagement with the interrupter-bar 6. Since this tripping action, in Fig. 2, occurs during an over current-condition, it is now desirable, at least in sectionalizer applications of the integrator-mechanism, to prevent the immediate opening or downward movement of the interrupter-bar 6, until the recloser (not shown) has interrupted the line-current. To this end, we have shown a means for temporarily holding the interrupter-bar in its upper (or closed) position, as described and claimed in the previously mentioned copending application of Andrew W. Edwards and Earl F. Beach.

Thus, as shown in Fig. 2 of our drawings, the horizontal arm 25, which is carried by the up-standing armature-rod 43, is pivotally connected to a retainer-pawl 50. Each time the armature-rod 43 moves upwardly to the overcurrent-position, the horizontal arm 35 rocks the retainer-pawl 50 into position under a corresponding shoulder 51 on the interrupter-rod 6, and said horizontal arm 35 lifts this retainer-pawl up substantially to the underside of said shoulder 51. Thus, in the final integrator-operation, when the rod-holding latch-pin 11 is unlatched, the interrupter-rod 6 does not immediately fall, because this rod is temporarily held up by the retainer-latch 50 as just described. This holding-action continues until the magnetizing coil 15 is deenergized, whereupon the interrupter-rod 6 moves downward under the bias of its spring 7, and the top end of this interrupter-rod is moved out of contact with the stationary line-contact 5, thus effecting the interrupter-action of the line-sectionalizer.

The sectionalizer of Fig. 2 may be reset by reclosing the interrupter-rod 6 with a switch-stick (not shown), and holding it closed for the brief

time which is required for the normal load-current in the line to heat up the bimetallic element or thermal time-delay device 38', whereupon the counter-rod 30 will be released and will reset itself by gravity, and the timer-circuit 39' will be opened by the disengagement of the holding-detent 37' from the latch 48 of the time-delay device. Then the integrator latch-pin 11 will hold the interrupter-rod in its elevated or closed position, and the switch-stick can be disengaged from the interrupter-rod 6.

It will be observed that, in either of the illustrated forms of our invention, we have provided inexpensive, and yet reliable, current-responsive time-delay means for controlling the release of a holding-detent in an integrator.

While we have described but two illustrative forms of embodiment of our invention, we wish it to be understood that we are not limited to the precise illustrated structures or combinations, and we desire that the appended claims shall be accorded the broadest construction consistent with their language.

We claim as our invention:

1. An integrator-mechanism comprising: an electromagnet-device having a magnetizing coil and having an armature which is movable from a predetermined unattracted position to a predetermined attracted position to which it is attracted by the magnetic flux produced by a predetermined overcurrent in the coil; a movable counter-member which is biased toward an inoperative position; a one-way drive-mechanism for imparting one step of a step-by-step advance to said counter-member each time said armature moves in one direction of its aforesaid movement; a holding-detent for at times holding said counter-member in advanced positions; and a current-responsive thermal time-delay device operable independently of the armature for at times making said holding-detent inoperative.

2. The invention as defined in claim 1, in combination with means for energizing the time-delay device with current responsive to the current traversing said coil.

3. The invention as defined in claim 1, in combination with means responsive to the current traversing said coil for energizing the time-delay device with current having a limited magnitude.

4. An integrator-mechanism comprising: an electromagnet-device having a magnetizing coil and having an armature which is movable from a predetermined unattracted position to a predetermined attracted position to which it is attracted by the magnetic flux produced by a predetermined overcurrent in the coil; a movable counter-member which is biased toward an inoperative position; a one-way drive-mechanism for imparting one step of a step-by-step advance to said counter-member each time said armature moves in one direction of its aforesaid movement; a holding-detent for at times holding said counter-member in advanced positions, said holding-detent being normally in an inoperative position; and a time-delay device, responsive to temporary overcurrent-values in said coil, for temporarily moving said holding-detent to an operative position independently of the armature.

5. The invention as defined in claim 4, characterized by said current-responsive time-delay device being thermally responsive.

6. An integrator-mechanism comprising: an electromagnet-device having a magnetizing coil and having an armature which is movable from a predetermined unattracted position to a prede-

termined attracted position to which it is attracted by the magnetic flux produced by a predetermined overcurrent in the coil; a movable counter-member which is biased toward an inoperative position; a one-way drive-mechanism for imparting one step of a step-by-step advance to said counter-member each time said armature moves in one direction of its aforesaid movement; a holding-detent for at times holding said counter-member in advanced positions; a current-responsive time-delay device for at times making said holding-detent inoperative; means for closing an energizing-circuit for said time-delay device when said counter-member is first advanced; and means for interrupting said energizing-circuit when the time-delay device makes said holding-detent inoperative.

7. The invention as defined in claim 6, characterized by said current-responsive time-delay device being thermally responsive.

8. An integrator-mechanism comprising: an electromagnet-device having a magnetizing coil and having an armature which is movable from a predetermined unattracted position to a predetermined attracted position to which it is attracted by the magnetic flux produced by a predetermined overcurrent in the coil; a movable counter-member which is biased toward an inoperative position; a one-way drive-mechanism for imparting one step of a step-by-step advance to said counter-member each time said armature moves in one direction of its aforesaid movement; a holding-detent for at times holding said counter-member in advanced positions; a current-responsive time-delay device for at times making said holding-detent inoperative; and means for closing an energizing-circuit for said time-delay device when said armature first moves to its overcurrent position.

9. The invention as defined in claim 8, in combination with means for interrupting said energizing-circuit when the time-delay device makes said holding-detent inoperative.

10. The invention as defined in claim 8, characterized by said current-responsive time-delay device being thermally responsive.

11. An integrator-mechanism comprising: an electromagnet-device having a magnetizing coil and having an armature which is movable from a predetermined unattracted position to a predetermined attracted position to which it is attracted by the magnetic flux produced by a predetermined overcurrent in the coil; a movable counter-member which is biased toward an inoperative position; a one-way drive-mechanism for imparting one step of a step-by-step advance to said counter-member each time said armature moves in one direction of its aforesaid movement; a holding-detent for at times holding said counter-member in advanced positions, said holding-detent being normally in an inoperative position; a current-responsive time-delay device; a normally open timer-circuit adapted, when energized, to supply the time-delay device with a current which is responsive to the current traversing said coil; means for closing said timer-circuit and setting the holding-detent in its operative position when the counter-member is first advanced; and means for causing said time-delay device, at the end of its time-delay period, to open said timer-circuit and set the holding-detent in its inoperative position.

12. The invention as defined in claim 11, characterized by said current-responsive time-delay device being thermally responsive.

13. An integrator-mechanism comprising: an electromagnet-device having a magnetizing coil and having an armature which is movable from a predetermined unattracted position to a predetermined attracted position to which it is attracted by the magnetic flux produced by a predetermined overcurrent in the coil; a movable counter-member which is biased toward an inoperative position; a one-way drive-mechanism for imparting one step of a step-by-step advance to said counter-member each time said armature moves to its unattracted position; a holding-detent for at times holding said counter-member in advanced positions, said holding-detent being normally in an inoperative position; and a time-delay device, responsive to temporary overcurrent-values in said coil, for temporarily moving said holding-detent to an operative position independently of said armature.

14. The invention as defined in claim 13, characterized by said current-responsive time-delay device being thermally responsive.

15. The invention as defined in claim 13, in combination with means responsive to the current traversing said coil for energizing the time-delay device with current having a limited magnitude.

16. An integrator-mechanism comprising: an electromagnet-device having a magnetizing coil and having an armature which is movable from a predetermined unattracted position to a predetermined attracted position to which it is attracted by the magnetic flux produced by a predetermined overcurrent in the coil; a movable counter-member which is biased toward an inoperative position, a one-way drive-mechanism for imparting one step of a step-by-step advance to said counter-member each time said armature moves to its overcurrent position; a holding-detent for at times holding said counter-member in advanced positions; a current-responsive time-delay device for at times making said holding-detent inoperative; means for closing an energizing-circuit for said time-delay device when said counter-member is first advanced; and means for interrupting said energizing-circuit when the time-delay device makes said holding-detent inoperative.

17. An integrator-mechanism comprising: an electromagnet-device having a magnetizing coil and having an armature which is movable from a predetermined unattracted position to a predetermined attracted position to which it is attracted by the magnetic flux produced by a predetermined overcurrent in the coil; a movable counter-member which is biased toward an inoperative position; a one-way drive-mechanism for imparting one step of a step-by-step advance to said counter-member each time said armature moves to its overcurrent position; a holding-detent for at times holding said counter-member in advanced positions, said holding-detent being normally in an inoperative position; a current-responsive time-delay device, a normally open timer-circuit adapted, when energized, to supply the time-delay device with a current which is responsive to the current traversing said coil; means for closing said timer-circuit and setting the holding-detent in its operative position when the counter-member is first advanced; and means for causing said time-delay device, at the end of its time-delay period, to open said timer-circuit and set the holding-detent in its inoperative position.

18. The invention as defined in claim 17, char-

acterized by said current-responsive time-delay device being thermally responsive.

19. The invention as defined in claim 17, in combination with: a response-member which is biased toward a responding position; a latch for normally holding said response-member from responding; means whereby the counter-member, at the termination of its predetermined step-by-step advance, releases said latch; and means whereby the armature, in its overcurrent position, interposes a temporary block against any substantial movement of the response-member in its responding direction.

20. An integrator-mechanism comprising: an electromagnet-device having a magnetizing coil and having an armature which is movable from a predetermined unattracted position to a predetermined attracted position to which it is attracted by the magnetic flux produced by a predetermined overcurrent in the coil; a movable counter-member which is biased toward an inoperative position; a one-way drive-mechanism for imparting one step of a step-by-step advance to said counter-member each time said armature moves to its overcurrent-position; a holding-detent for at times holding said counter-member in advanced positions, said holding-detent being normally in an inoperative position; a current-responsive time-delay device; a normally open timer-circuit adapted, when energized, to supply the time-delay device with a heating-current; means responsive to the current traversing said coil for providing a source of current of limited magnitude for said timer-circuit; means for closing said timer-circuit and setting the holding-detent in its operative position when the counter-member is first advanced; and means for causing said time-delay device, at the end of its time-delay period, to open said timer-circuit and set the holding-detent in its inoperative position.

21. The invention as defined in claim 20, in combination with: a response-member which is biased toward a responding position; a latch for normally holding said response-member from responding; means whereby the counter-member, at the termination of its predetermined step-by-step advance, releases said latch; and means whereby the armature, in its overcurrent position, interposes a temporary block against any substantial movement of the response-member in its responding direction.

22. Circuit interrupting apparatus comprising separable contacts, electroresponsive means operable in response to a predetermined value of current, a movable counter member, a one-way drive mechanism for imparting one step of a step-by-step advance to said counter member in response to operation of the electroresponsive means for eventually making it effective to retain said contact means separated, and a thermally responsive time delay holding device for holding said counter member in an advanced position for a predetermined time, said time delay device having a thermal element responsive to the current of said electroresponsive means.

23. A circuit interrupter comprising, separable contacts, electroresponsive means operable in response to an overcurrent, a counter member operable to effect separation of said contacts, means operable in response to operation of said electroresponsive means for imparting one step of a step-by-step advance to said counter member for effecting separation of said contacts upon a predetermined number of such steps, and a

time delay detent actuated to retain said counter member in an advanced position including a thermal-responsive element disposed to be operated a predetermined time after cessation of the overcurrent in accordance with the current through said electroresponsive means to effect a delayed release of said counter member.

24. A circuit interrupter comprising, separable contacts, electroresponsive means operable in response to a current of a predetermined value, a counter having a member actuated by the electroresponsive means to advance in a step-by-step relation to effect retention of said contacts in a separated position, and means including a thermally responsive element having a releasable detent portion engaging the counter to hold it in an advanced position for a predetermined time.

25. A circuit interrupter comprising, separable contacts, electroresponsive means operable in response to an overload, means including a movable counter disposed to effect retention of said contacts in a separated condition in response to a predetermined number of counting operations, a one-way drive mechanism for imparting a one step advance of a step-by-step counting operation in response to each operation of the electroresponsive means, a holding detent for holding said counter member in an advanced position, and time delay means including a thermal responsive device responsive to the current in said electroresponsive means for rendering said detent inoperative a predetermined time after deenergization of said electroresponsive means.

26. In a circuit interrupter, separable contacts, electroresponsive means having an armature movable in response to an overcurrent, means biasing the armature to return to a normal position upon termination of the overcurrent, a counter member movable a predetermined distance to effect separation of said contacts, means imparting one step of a step-by-step movement to said counter member each

time the armature returns to its normal position for effecting advancement for said predetermined distance, and means including a thermal element responsive to current in said electroresponsive means, said thermal element having a detent portion for retaining said counter member in an advanced position for a predetermined time.

27. A circuit interrupter comprising, separable contacts, electroresponsive means having an armature movable in response to an overload, a counter member operable a predetermined distance to effect separation of said contacts, means biasing said counter to return it to a normal position upon termination of the overload, means imparting one step of a step-by-step advance to said counter member each time the armature moves in response to an overload for eventually effecting movement for said predetermined distance, holding means operable to retain the counter member in an advanced position, means including a thermally-responsive time delay element operable to maintain the holding means in an operative position and actuated in response to current through the electroresponsive means to release said holding means to an inoperative position a predetermined time after normal energization of the electroresponsive means, and means for preventing separation of said contacts while the armature is moved in response to an overload.
